UNITED STATES PATENT OFFICE.

ALDEN CHARLES NICKLOY, OF GLOVERSVILLE, NEW YORK.

REFILLED-BOTTLE DETECTOR.

SPECIFICATION forming part of Letters Patent No. 728,963, dated May 26, 1903.

Application filed September 27, 1902. Serial No. 125,040. (No model.)

To all whom it may concern:

Be it known that I, ALDEN CHARLES NICKLOY, a citizen of the United States, and a resident of Gloversville, Fulton county, New York, have invented certain new and useful Improvements in Refilled-Bottle Detectors, of which the following is a specification.

The object of my invention is to provide means for indicating if a bottle has been re-filled after having been emptied of its contents; and the invention comprises the novel details of improvement, that will be more fully hereinafter set forth and then pointed out in the claims.

Reference is to be had to the accompanying drawings, forming part hereof, wherein—

Figure 1 is a vertical section through the neck of a bottle provided with my improvements. Fig. 2 is a cross-section on the line 2-2 in Fig. 1. Fig. 3 is a cross-section on the line 3-3 in Fig. 1. Fig. 4 is a detail side view of the protector at the outer end of the bottle-neck. Fig. 5 is a similar view showing the locking device in the locked position. Fig. 6 is a vertical section of said protector, the locking device being removed; and Fig. 7 is a detail view of the locking device.

Similar characters of reference indicate corresponding parts in the several views.

In the drawings the numeral 1 indicates the neck of a bottle, and within said neck, preferably near the inner end, is secured a partition, stopper, or cork 2, which is provided with a bore or passage a^2 through it.

Within the neck 1 and secured to the partition 2 in line with the bore a^2 is a tube 3, preferably of glass, extending part way up the neck of the bottle, and around the tube 3 is a tube 4, which is secured to the partition 2 and is of less length than the tube 3, so as not to project so far as the upper end of the latter. The tube 4 is of greater diameter than the tube 3, so as to provide between said tubes a chamber or space 5, within which a detector 6 is located. Between the tubes 3 and 4 and the neck 1 a chamber 7 is provided, the bottom of which chamber is formed by the partition 2, the arrangement being such that if liquid rises in the chamber 7 it will first flow over the upper end of the tube 4 into the chamber 5 before passing into the tube 3. The tube 3 at its outer end is provided with

a flange or extension 3^a, which extends over the tube 4, so as to act as a shield to prevent drippings from falling into the chamber 5. 55

The detector 6 which I preferably use consists of material that is adapted to change color when liquid encounters the same, and to this end I provide a strip or tube of paper or cloth saturated with anilin or analogous substance, 60 and around the same I place a strip or tube of paper or cloth, preferably white, which can be readily seen through the glass of the bottle-neck 1 and the tube 4. The detector 6 is placed in the chamber 5 in a dry state, 65 and if liquid is poured back into the bottle-neck it will rise in chamber 7 and enter chamber 5, and thereby cause the white paper or cloth of the detector to become discolored, owing to the action of the liquid on the anilin substance, the color of the latter being communicated to said paper or cloth, and when it is seen that the detector is discolored it will be an indication that the bottle has been refilled. 75

8 indicates a stopper for the tube 3 to act as an ordinary closure for the bottle.

To prevent access to the tubes and the detector and to require any liquid that is poured into the bottle-neck to first enter the chamber 7 before entering the tube 3, I provide within the bottle-neck 1 beyond the tube 3 a protector or block 9, that fits within the bottle-neck and is smaller than the same to permit the passage of liquid between the protector and the neck, and at the same time the protector is larger than the tube 3, so as to extend over the same, the protector 9 being at a distance from the outer end of tube 3. The protector or block 9 is shown provided with a recess 9^a, (see Fig. 6,) that is aligned with the stopper 8 and adapted to receive the same more or less, said stopper being shown provided with a stem or wire 8^a, that passes through the block 9 and is provided at its outer end with a head or enlargement 8^b for manipulating the stopper. The block 9 may be secured in the bottle-neck in any desired manner, and for convenience in placing the stopper in the bottle-neck and for securing it there I have shown the block 9 provided with a stem 10 on one side and with a movable head 11 at the opposite side that enters a socket 9^b in the block 9, and 95 100

the head 11 has a stem 11^a, alined with the stem 10. Means are provided for locking the head 11 to the block 9, and in the construction shown the head 11 is shown provided with pins 12, projecting outwardly and normally held in an outward position by a spring 13, (see Fig. 7,) the pins 12 being adapted to enter grooves 14 in the wall of socket 9^b, which may be beveled to permit the pins 12 to ride into said socket, and within the socket at a distance from the grooves 14 are seats 15, adapted to receive the pins 12. When the block 11 is inserted in socket 9^b, the pins 12 pass through the grooves, and when the head 11 is turned the pins 12 spring into the seats 15 and positively lock the head 11 in block 9. The stems 10 and 11^a are adapted to be received in sockets or an annular recess 1^b in the neck 1. To apply the block 9 to the bottle-neck, the head 11 is inserted in the socket 9^b sufficiently far to permit the stems 10 and 11^a to slide into the bottle-neck, and when the stems are alined with the sockets or recess 1^b the head 11 is pushed laterally outwardly to cause the stems 10 and 11^a to enter 1^b, and then the head 11 is rotated until the pins 12 enter the seats 15, and the block is permanently locked in the bottle-neck against removal.

As a protection against the entrance of dirt and foreign matter into the bottle-neck I preferably provide the outer end with a disk or stopper 16, which may be readily removed when the bottle is to be used.

In assembling the parts the stopper or cork 2, with the tubes 3 and 4 attached to it, and the detector 6, located in the chamber 5, are secured in the bottle-neck, preferably after the bottle has been filled with liquid, and the stopper 8 is secured in the tube 3, and then the block or protector 9 is secured in the bottle-neck, as described, the stem 8^a being passed through the same and the cap 16 secured in place. When the bottle is to be used, the cap 16 is first removed and the stem 8^a pulled outwardly to remove the stopper 8 from tube 3, and said stopper is drawn into the recess 9^a in block 9, and then the stem or wire 8^a may be bent down to hold the stopper 8 to the block. Liquid may now readily be poured through the tube 3, and it will pass around the block 9 and out of the bottle-neck. If an attempt should be made to refill the bottle, the block 9 would compel the liquid to first enter chamber 7 before entering tube 3, and as the liquid rises and flows into chamber 5 it necessarily will reach the detector 6, and thus the discoloration of the same will occur, after which liquid can pass through tube 3 into the bottle. Nevertheless the fact of refilling the bottle will be indicated by the discoloration of the detector.

Having now described my invention, what I claim is—

1. A bottle provided with a partition or stopper in its neck and a tube within the neck provided with a detector comprising

material that will change color upon liquid engaging the same, substantially as described.

2. A bottle having a partition or stopper in its neck, a pair of concentric tubes located in the neck, one of which tubes is longer than the other and communicates with the interior of the bottle, said tubes providing a chamber, and a detector within said chamber comprising material that will change color upon liquid engaging the same, substantially as described.

3. A bottle having a partition or stopper in its neck, a pair of concentric tubes located in the bottle-neck, one of which tubes is longer than the other and communicates with the interior of the bottle, said tubes providing a chamber, a detector within said chamber comprising material that will change color upon liquid engaging the same, and a block or protector within the bottle-neck at a distance beyond said tubes and of a greater width than the tubes to direct incoming liquid away from the tubes and the bottle-neck, substantially as described.

4. A bottle-neck having a tube within it and a detector comprising material having a substance applied to it that will change color upon being engaged by liquid, and a piece of paper or the like surrounding said material and adapted to be discolored by the substance on said material reaching it, substantially as described.

5. A bottle having a partition or stopper in its neck, a pair of concentric tubes located in the bottle-neck, one of which tubes is longer than the other and communicates with the interior of the bottle, said tubes providing a chamber, a detector within said chamber comprising material that will change color upon liquid engaging the same, a block or protector within the bottle-neck at a distance beyond said tubes and of a greater width than the tubes to direct incoming liquid away from the tubes and the bottle-neck, said block having a recess facing the tubes, and a stopper for the inner tube provided with a stem adapted to be drawn outwardly to cause the stopper to enter the recess in the block, substantially as described.

6. A bottle provided with a partition in its neck having a bore, a tube alined with said bore and extending into the bottle-neck, a tube surrounding the first-named tube and secured to the partition providing a chamber between said tubes, the first-named tube being longer than the second-named tube, a chamber being formed between the neck, the tubes and the partition, a detector comprising material that will change color upon liquid reaching the same, a stopper for the first-named tube, a block or protector secured in the neck beyond said tubes and adapted to permit liquid to pass along the same, and means for withdrawing the stopper from said tube, substantially as described.

7. A bottle provided with a detector in its neck composed of material that will change color upon liquid reaching the same, combined with a block located in the bottle-neck, 5 said block having a stem on one side, and a movable head on the other side provided with a stem, the bottle-neck having a recess or depression to receive said stems, said head having means for locking it to said block, substantially as described.

8. A bottle provided with a detector in its neck composed of material that will change color upon liquid reaching the same, combined with a block located in the bottle-neck,

15 said block having a stem on one side and a head on the other side provided with a stem, the bottle-neck having a recess or depression to receive said stems, said block having a socket to receive said head and the walls of the socket having a recess and a seat, said 20 head having a spring-pressed pin adapted to pass into said recess and seat to lock the head to the block thereby securing the block in the bottle-neck, substantially as described.
